UNITED STATES PATENT OFFICE.

ADOLF SPIEL, OF BERLIN, GERMANY.

PETROLEUM-ENGINE.

SPECIFICATION forming part of Letters Patent No. 393,127, dated November 20, 1888.

Application filed May 13, 1887. Serial No. 238,152. (No model.)

To all whom it may concern:

Be it known that I, ADOLF SPIEL, of Berlin, Germany, have invented a new and Improved Petroleum-Engine, of which the following is a full, clear, and exact description.

The object of my invention is to provide a new and improved petroleum-engine in which the explosion of a mixture of petroleum and air forms the motive power.

10 The invention consists in the construction and arrangement of various parts and details and combinations of the same, as will be fully described hereinafter, and then pointed out in the claims.

15 Reference is to be had to the accompanying drawings, forming a part of this specification, in which similar letters of reference indicate corresponding parts in all the figures.

Figure 1 is a side elevation of my improvement with parts in section. Fig. 2 is a plan view of the same with the cylinder and its connections in section. Fig. 3 is an enlarged end view of the cylinder end. Fig. 4 is a diagram illustrating the motion of the cylinder-piston and oil-pump piston. Fig. 5 is a longitudinal sectional elevation of the engine-governor. Fig. 6 is an enlarged sectional plan view of the cylinder end on the line $y-y$ of Fig. 3. Fig. 7 is a longitudinal sectional elevation of the cylinder; and Fig. 8 is a vertical cross-section of the same on the line $x-x$ of Figs. 1 and 7.

20 My improvement is mounted on a suitably-constructed frame supporting the cylinder A, which is open at its inner end, and is provided with the usual piston-head, driving-shaft, and intermediate connections. The outer end of the cylinder is closed by a head, B, provided with the inwardly-opening valve g , which admits a mixture of air and petroleum into the cylinder from the channel g' , formed in the said cylinder-head B. The channel g' is connected with the air-inlet pipe h , and into this channel g' opens the end a' of the oil-supply pipe a , connected with an oscillating oil-chamber pivoted with its cylinder d' at e to a bracket of the main frame.

25 The piston-rod d of the cylinder d' is provided with the head e , having a slot, c' , into which projects the crank-pin f , secured to the disk m , secured to the shaft b , carrying the bevel gear or friction wheel b' , meshing into a

similar wheel, b^2 , secured to the main driving-shaft. The gear-wheels b' and b^2 have a proportion of one to two, so that each revolution of the main shaft imparts one half-revolution to the said shaft b .

30 In the piston-rod head c screws the screw r , extending with its lower end into the slot c' and serving to regulate the stroke of the oil-pump. The latter is connected by the pipe a^2 with the oil-reservoir x , located in the hollow lower part of the frame carrying the engine.

35 The pipe a^2 is provided with a valve, i , operated from the governor l , so as to regulate the supply of oil according to the speed of the engine, thus increasing or diminishing the speed of said engine. The valve i is provided with a valve-rod, k , pointed at its lower end and adapted to regulate the flow of oil in the pipe a^2 , on being moved up or down, by the 40 action of the governor l , which may be of any approved construction. The rod k is held at its lower end in the pipe k' , which is secured to the valve i , and extends above the level of the oil-reservoir x , so that no stuffing-boxes 45 are required on the said valve i for the said rod k .

45 The disk m , secured on the shaft b , is provided on its rim with a cam, m' , adapted to operate the valve n , fitted in the head B, and serving to establish a communication between the outlet of the cylinder A and the igniting-chamber p by means of the channel o , which is opened and closed by said valve n . The outward motion of said valve n is limited by 50 the stop n' , and a yielding connection is made with the cam m' by the bolt n^2 , held against said cam m' by a spring, n^3 , held in said valve n . This spring also forces the valve n upon its seat in the channel o . In the igniting-chamber p is held a light or lamp, of any suitable construction, for igniting the charge of gas and oil, in a manner hereinafter more fully explained. In the outer end of the cylinder A is formed a sidewardly-extending channel, q , 55 in which is held a valve, q' , opening outward and serving as an exit for the products of combustion.

60 The operation is as follows: The piston in the cylinder A when traveling forward sucks in air through the air-pipe h , and at the same time the oil-chamber forces a quantity of oil through

the end a' of the pipe a into the channel g' , so that a complete mixture of the air and the oil takes place, and this mixture passes into the cylinder through the valve g , which is opened 5 by the suction of the forward movement of the piston. On the return stroke of the piston the valve g is closed and the mixture in the cylinder is compressed, as this mixture cannot escape through the channel o , which is held 10 closed by the valve n , pressed inward by the action of the cam m' of the disk m , secured to the shaft b . When the piston is near the end of its stroke, then the cam m' releases the bolt n^2 , thus freeing the valve n , which is forced 15 outward against the stop n' by the pressure of the compressed mixture in the cylinder, part of which mixture now passes into the igniting- 20 tube p and is ignited by the light or lamp therein, thus igniting the entire charge in the 25 outer end of the cylinder, and thus causing an explosion, the force of which propels the piston forward and imparts motion to the main driving-shaft. On the return-stroke of the piston the valve n is again seated on 30 the channel o , and the products of combustion are forced outward into the channel g and through the valve g' to the outside. The oil-pump draws oil from the reservoir x at the last return movement of the piston 35 35 and again forces the oil into the channel g' on the forward motion of the piston, as above described. Thus it will be seen that the piston makes two complete strokes to one movement of the oil-pump. When the engine exceeds its normal speed, then the balls of the governor 40 40 l cause the rod k to move downward, thereby either entirely closing the opening i^2 or closing it partly only, so as to admit no or little oil from the oil receptacle x into the pipe a^2 . The supply of oil will thus be diminished, and the mixture of air and oil will be weakened, thus producing an explosion of less force, and thereby reducing the speed of the engine 45 to the normal condition, so that the governor again lifts the rod k and admits a full supply of oil to the channel g' .

The throw of the pump is regulated by the screw r , which is adjusted in the head c , so as to increase or diminish the upward and downward motion of said head c and the piston-rod d .

In my application, Serial No. 242,946, filed June 30, 1887, I show and describe the oil-pump and an igniting device of a special construction, which I do not claim in this application.

Having thus fully described my invention, I claim as new and desire to secure by Letters Patent—

60 1. In a petroleum-engine, the combination, with a cylinder and piston traveling in the said cylinder, of a cylinder-head secured to the outer end of said cylinder and provided with the channels g' and o , the valve g , held on 65 said head in said channel g' , and opening inward, the air-supply pipe h , connected with

said channel g' , the petroleum-supply pipe a , opening into said channel g' , and an oil-pump for supplying said pipe a with oil, substantially as shown and described.

70

2. In a petroleum-engine, the combination, with a cylinder and a piston traveling in said cylinder, of a cylinder-head secured on the outer end of said cylinder and provided with the channels g' and o , the valve g , held on said head in said channel g' , and opening inward, the air-supply pipe h , connected with said channel g' , the oil-supply pipe a , opening into said channel g' , the igniting-chamber p , and the valve n , adapted to connect the said igniting-chamber p with the said channel o , leading into the cylinder, substantially as shown and described.

75

3. In a petroleum-engine, the combination, with a cylinder and a piston traveling in said cylinder, of a cylinder-head secured on the outer end of said cylinder and provided with the channels g' and o , the valve g , held on said head in said channel g' , and opening inward, the air-supply pipe h , connected with 85 said channel g' , the oil-supply pipe a , opening into said channel g' , the igniting-chamber p , supporting a light or lamp, the valve n , adapted to connect the said igniting-chamber p with said channel o , leading into the cylinder, and means, substantially as described, for 90 operating said valve n from the main driving-shaft, as set forth.

95

4. In a petroleum-engine, the combination, with a cylinder and a piston traveling in said cylinder, of a shaft, b , operated from the main driving-shaft, the cam-disk m , secured to the said shaft b , the bolt n^2 , held against said cam-disk by a spring, n^3 , the valve n , supporting said spring and operated by said rod n^2 , and the igniting-chamber p , connected with the interior of said cylinder by said valve n and the channel o , substantially as shown and described.

100

5. In a petroleum-engine, the combination, with a cylinder and a piston traveling in said cylinder and imparting a rotary motion to the main driving-shaft, of means, substantially as described, for imparting a rotary motion to the auxiliary shaft b , the auxiliary shaft b making one revolution to two strokes of the said piston, an oscillating oil-pump operated from said auxiliary shaft b for forcing at every two strokes of said piston a quantity of oil into the channel g' , connected with 115 the interior of the cylinder, substantially as shown and described.

110

6. In a petroleum-engine, the combination, with the rod k , of the sleeve k' , the valve-case i , supporting said sleeve k' , and the oil-receptacle x , supplying said valve-case i with oil by means of the pipe a^2 , substantially as shown and described.

125

7. In a petroleum-engine, the combination, with the auxiliary shaft b , of the disk m , secured on said shaft, the crank-pin f , fastened on said disk, the head c , having the slot c' , in

130

which the said crank-pin *f* operates, the regulating-screw *r*, screwing on said head, the piston-rod *d*, connected with said head *c*, the cylinder *d'*, in which operates the said piston-rod supporting the piston, said cylinder being pivoted at *e*, and the oil inlet and outlet pipes *a* and *a'*, leading to the lower end

of said cylinder *d'*, substantially as shown and described.
